US0D1023954S

(12) **United States Design Patent** (10) Patent No.: **US D1,023,954 S**
(45) Date of Patent: ** Apr. 23, 2024

(54) **PORTABLE BACKUP POWER SUPPLY UNIT**

(71) Applicant: **FUJIAN SUPER SOLAR ENERGY TECHNOLOGY CO., LTD.**, Xiamen (CN)

(72) Inventors: **Hesheng Liu**, FuJian (CN); **Jianbin Wang**, FuJian (CN); **Dongdong Lai**, FuJian (CN)

(**) Term: **15 Years**

(21) Appl. No.: **35/517,148**

(22) Filed: **Apr. 6, 2023**

(80) **Hague Agreement Data**

Int. Filing Date: **Apr. 6, 2023**

Int. Reg. No.: **DM/228597**

Int. Reg. Date: **Apr. 6, 2023**

Int. Reg. Pub. Date: **May 12, 2023**

Primary Examiner — Rosemary K Tarcza

(57) **CLAIM**

The ornamental design for a portable backup power supply unit, as shown and described.

DESCRIPTION

The patent or application file contains at least one drawing executed in color. Copies of this patent or patent application publication with color drawing(s) will be provided by the Office upon request and payment of the necessary fee.

1. Portable backup power supply unit

1.1 : Front

1.2 : Back

1.3 : Left

1.4 : Right

1.5 : Top

1.6 : Bottom

1.7 : Perspective
